UNITED STATES PATENT OFFICE.

CHRISTOPHER MOELLER, OF NEWARK, NEW JERSEY.

IMPROVEMENT IN WICK-HOLDERS FOR ARGAND LAMPS.

Specification forming part of Letters Patent No. 14,248, dated February 12, 1856.

To all whom it may concern:

Be it known that I, CHRISTOPHER MOELLER, of Newark, in the county of Essex and State of New Jersey, have invented an Improvement in Wick-Holders for Argand Lamps; and I do declare that the following is a full, clear, and exact description of the principle or character which distinguishes it from all other things before known, and of the usual manner of making, modifying, and using the same, reference being had to the annexed drawings, in which—

Figure 1 represents a perspective view of the wick-holder and tube; Fig. 2, a vertical middle section through Fig. 1; Fig. 3, a side view of the wick-holder.

My invention consists in an improvement in holding the wick in that kind of Argand lamps in which a circular wick is used and the wick-holder is attached to and raised and lowered by rack and pinion or screw without turning the wick-holder round in its ascent and descent. Various devices have been used in such lamps for holding the wick to the holder—such as tying the wick upon a collar on the holder, clasping the wick by springs upon a core or short cylindrical piece within the wick, or clasps made to seize the wick upon the core and exert spring-pressure upon the wick as the clasps are drawn down within the wick-tube.

My invention is an improvement upon these modes, as it is more simple, efficacious, and economical, and is described as follows: The wick-holder consists of a number of elastic

fingers *a a*, more or less according to the size of the wick, which are attached to or proceed from the ferrule *b*, fixed to the upper end of the rack *d*. These fingers have two curves *e e'*, the upper one of which *e'* presses against the inner tube *k*, and by virtue of its spring or elasticity causes the extremity of the finger to press the wick firmly against the outer tube *k'* during the rise and fall of the wick-holder. The wick is put upon this wick-holder with great facility by compressing the fingers, inserting them within the end of the wick, and then suffering the fingers to expand by their elasticity. The wick is thus held securely and the friction of the wick and fingers upon the tubes is such that the rack cannot fall by any sudden jarring of the lamp and draw the wick down with it. This mode of raising and lowering the wick is very desirable for lamps for railroad-cars, but has been attended with much trouble heretofore on account of the occasional falling of the wick from sudden shocks, a difficulty completely remedied by my invention.

I do not claim a spring-clasp for embracing the wicks of lamps; but

I claim—

The peculiar mode hereinabove set forth of holding the wick and pressing it outwardly against the wick-tube, in the manner and for the purposes herein set forth.

CHRISTOPHER MOELLER.
